UNITED STATES PATENT OFFICE.

EUGENE J. JALBERT, OF PROVIDENCE, RHODE ISLAND.

OIL BURNER.

Application filed December 23, 1925. Serial No. 77,370.

My invention relates to oil burners, particularly to comparatively small oil burners adapted for house heating purposes provided with a gravity oil feed.

I am aware that burners of a similar type to mine have been hitherto provided, comprising a burner bowl, usually provided with a burner cone having means to supply oil upwardly therein, said means usually comprising a small pipe, and means to deflect air downwardly on said burner cone or bowl. The oil however, has not become vaporized until it is discharged out of the oil supply duct and trickles over the burner cone, and is usually ignited just after vaporizing. Due to this fact the small oil supply inlet pipe has usually become clogged with carbon. Employing my invention, which comprises merely inserting the base of a T pipe-fitting in the oil supply duct the T pipe-fitting acts as an oil vaporizer to thoroughly vaporize the oil before it is discharged in transverse jets above the burner cone.

One object of my invention therefore is to provide I believe for the first time a fuel vaporizer in burners of this description.

A further object of my invention is to provide a more efficient oil burner of this type than hitherto provided by thoroughly vaporizing the oil before ignition. It is obvious that the upper portion of the transverse portion of the T pipe-fitting deflects the oil vapor downwards so that it can be thoroughly vaporized before being discharged in said transverse jets and that the upper portion of the transverse portion of said T pipe-fitting thus acts as a deflector plate for this purpose.

A further object of my invention is to provide an oil vaporizer in this type of burner cheap, simple of construction and which is readily detachable from the oil supply duct and which may be readily cleaned.

A further object of my invention in its preferred embodiment is to so lengthen the oil supply duct that it may be acted upon by the flames and the downwardly discharged preheated air so that the oil in the vaporizer may be more readily vaporized before discharge and later ignition.

A further object of my invention in its preferred embodiment is to mix with the preheated air sufficient vaporized oil for proper combustion.

These and such other objects of my invention as may hereinafter appear will be best understood from a description of one embodiment thereof such as is shown in 60 the accompanying drawings.

In the drawings, Fig. 1 is a perspective view of a house heating furnace having the wall thereof partially broken away to show an oil burner constructed in accordance 65 with my invention installed therein, the oil supply pipe therefor and an oil storage tank connected thereto.

Fig. 2 is a plan view of my improved oil burner.

Fig. 3 is a cross sectional view thereof taken along the lines 3—3 of Fig. 2.

Fig. 4 is a plan view of the modified T pipe-fitting vaporizer I employ.

Fig. 5 is a side elevation of the improved 75 modified type of T pipe-fitting vaporizer.

Fig. 6 is a diagrammatic sectional view illustrating the vaporization of the oil in the T pipe-fitting.

In the drawings, wherein like characters 80 of reference indicate like parts throughout, 10 illustrates a house heating furnace. To install my improved oil burner 12 in furnaces of this type it is not necessary even to remove the grate, the burner bowl 14 of my 85 improved burner is merely laid substantially in the center of the grate and the air conduit 16 and vaporizer 18 suitably mounted thereon. To insure the proper draft for the oil burner 12 the annular portion 20 of 90 the grate 21 around the burner bowl is preferably suitably covered with asbestos 22 or other suitable material to prevent the draft from coming up therethrough and to insure that all the draft will come up through the 95 air inlet openings 24 of the burner bowl 14. An oil tank 26 is suitably mounted preferably adjacent to the furnace 10 and suitably connected by a pipe 28 to the oil burner 12 in a manner to be described. 100

As stated, the preferred embodiment of my invention comprises three parts, namely the burner bowl 14, the air conduit 16 and the oil vaporizer 18. The burner bowl 14 is provided with the depending annular 105 exterior flange 30 for mounting it on the furnace grate 21. Depending from the upper ends of said annular flange or cylinder 30 is the bowl 32 of usual configuration. It is over the bowl surface 32 that the oil vapor 110 is ignited. While I have shown in my preferred embodiment a true bowl or pan 32

it is obvious that parts of it may be dispensed with and I therefore employ the word "bowl" to include any suitable ignition surface of true bowl shape or otherwise. The outer edge of the bowl 32 is preferably provided with a plurality of upstanding air inlet openings 24 preferably two as shown in the drawings preferably spaced at diametrically opposite points on the outer edge of said bowl surface 32. I also preferably provide preferably substantially near the center of the bowl 32 a centrally upstanding burner cone 36. In my preferred embodiment said burner cone 36 is provided with a plurality of radially spaced annular grooves 38 arranged one above another in stepped relationship. Though said burner cone 36 functions to more thoroughly vaporize any oil which may not be thoroughly vaporized by the vaporizer 18 it may be dispensed with. In the claims I employ the word "cone" in the general sense used in the art as defining its function rather than its configuration. The bowl is provided with the oil inlet duct 40 which preferably extends substantially centrally vertically of the cone 36. Said oil inlet duct 40 is suitably connected as at 29 to the oil supply pipe 28.

30 To provide means to discharge air downwardly upon the burner cone I preferably provide the air supply conduit 16 overarchingly said burner bowl. Said conduit 16 is preferably provided with the down turned ends 42 adapted to be connected to said upstanding air inlet ducts 24 of the burner bowl. Though in my preferred embodiment I have shown the bowl member 14 provided with two upstanding inlet openings, and the air supply conduit provided with two cooperating downturned ends 42 adapted to register with said air inlet openings 24, it is obvious that a plurality of said cooperating air inlet openings and downturned ends may be provided if desired. The bowl member 14 and conduit member 16 are so constructed that when the conduit 16 is laid upon the bowl 14, the downturned ends 42 will register with the air inlet openings 24. To insure that this flush fit takes place I preferably provide the outer edges of the bowl 14 exterior of said air inlet openings 24 with the upstanding curved ribs 44. Said conduit 16 is also provided with the preferably central air discharge opening 48 disposed over the burner cone 36. I preferably provide the portion of the conduit directly above the discharge opening with the downwardly deflected portion 46 to provide surfaces for deflecting the heated air down through the discharge opening 48.

60 In addition, I provide an oil vaporizer 18 to be attached to the burner bowl 14 to vaporize the oil prior to ignition, said vaporizer being preferably adapted to discharge

vapor outwardly of the burner bowl in transverse jets. In my preferred embodiment said vaporizer 18 preferably comprises the T pipe-fitting 18, said T pipe-fitting being provided with the usual depending base 50 and upper transverse portion 52. In my preferred embodiment I preferably construct the lower portion 54 of the base 50 thereof of smaller diameter than the upper portion 56, the lower portion 54 being approximately the diameter of the air inlet duct 40 to compactly register therein and to provide the annular shoulder 58 to vertically position said vaporizer 18 within said oil inlet duct 40. In my preferred embodiment, the burner cone 36 and the T pipe-fitting are of such a height that the ends 60 of the transverse portion 52 of said T pipe-fitting will discharge substantially flush with the lower annular end 47 of the depending annular air discharge opening 46 of the air supply conduit 16. It is obvious that the upper portion 62 of the transverse portion 52 of the T pipe fitting may provide deflecting means to deflect the oil and vapor downwards to more thoroughly vaporize it before it is discharged in transverse radial jets 64 from said vaporizer 18. In case the oil should not be properly ignited due to a poor grade thereof or for any other reason, I provide the bowl 14 with the overflow hole 70 through which unconsumed oil may flow, and I provide the return duct 72 leading from said hole to a suitable trap 74 connected to the oil inlet pipe 28.

The operation of my invention is obvious from the above description. The usual draft in the furnace sucks air through the air inlet openings 24 through the air supply conduit 16 and discharges it downwardly over the vaporizer 18, burner cone 36 and bowl surface 32. The oil 66 is fed by gravity from the tank 26 through the piping 28 and upwards through the oil supply duct 40. As explained the oil vapor is ignited over the burner cone 36 and bowl surface 32 after it has been discharged in transverse jets from the vaporizer 18, the flames spreading over the entire burner cone 36, at least the center portion of the bowl 32 and around the air supply conduit 16. It is obvious that the air coming up through the air supply conduit is to a certain degree preheated by the counter current principle before coming in contact with the oil. It is obvious that due to the intense heat of ignition and combustion that the upper end 68 of the oil supply duct 40 and the entire vaporizer 18 will be tremendously heated. Fig. 6 illustrates how the oil is vaporized before being discharged. Being thus subjected to this tremendous heat it becomes partially vaporized before leaving the upper end 68 of the duct 40. As the oil and

oil vapor rushes up through the base 50 of the vaporizer 18, it is obvious that it strikes the upper portion 62 of the transverse portion 52 of the T pipe-fitting and as shown in Fig. 6 is deflected downwards as at 70, and then due to the draft present is sucked outwards above the burner cone in the transverse jets 64 for ignition. The oil vapor 65 then is met by the down rush of air from the air supply conduit 16 and is ignited as explained over the bowl 32, the cone 36 and adjacent portions of the air supply conduit 16.

It is obvious that I have provided in an oil burner of the gravity feed type means to thoroughly vaporize the oil before ignition, said means being simple in construction, readily cleaned, cheap and readily attached.

It is understood that my invention is not limited to the embodiment shown and that various deviations may be made therefrom without departing from the spirit and scope of the appended claims.

What I claim as new and desire to secure by Letters Patent is:

1. An oil burner, comprising a burner bowl having a plurality of upstanding air inlet openings spaced at diametrically opposite points near the outer edge thereof, a central upstanding burner cone formed with radially spaced annular grooves in stepped relationship having an oil inlet duct extending substantially centrally vertically thereof, an air supply conduit overarching said burner bowl having downturned ends connected to said upstanding air inlet openings of the burner bowl and a depending air discharge opening disposed over said burner cone, said conduit having the portion above the discharge opening downwardly deflected to provide surfaces for deflecting the heated air down through said discharge opening and a fuel vaporizer comprising a T pipe-fitting, the lower portion of the base thereof being of smaller diameter than the upper to register within said oil inlet duct and to form a shoulder to position it therein, each end of the transverse portion thereof discharging substantially flush with the lower end of the depending air discharge opening of said air supply conduit whereby the upper portion of the transverse portion of said T pipe-fitting may provide deflecting means to more thoroughly vaporize the oil before discharge from said fitting and ignition.

2. An oil burner, comprising a burner bowl having air inlet openings, and a central upstanding burner cone, having an oil inlet duct extending substantially vertically thereof, an air supply conduit overarching said burner bowl having downturned ends connected to said air inlet openings of the burner bowl and a depending air discharge opening disposed over said burner cone and a fuel vaporizer comprising a T pipe-fitting

adapted to register within said oil inlet duct.

3. An oil burner, comprising a burner bowl having a plurality of upstanding air inlet openings spaced at diametrically opposite points near the outer edge thereof and a central upstanding burner cone having an oil inlet duct extending substantially centrally vertically thereof, an air supply conduit overarching said burner bowl having downturned ends connected to said upstanding air inlet openings of the burner bowl and a depending air discharge opening disposed over said burner cone and a fuel vaporizer comprising a T pipe-fitting adapted to register within said oil inlet duct.

4. An oil burner, comprising a burner bowl having a plurality of air inlet openings and a central upstanding burner cone formed with radially spaced annular grooves in stepped relationship having an oil inlet duct extending substantially centrally vertically thereof, an air supply conduit overarching said burner bowl having downturned ends connected to said air inlet openings of the burner bowl and a depending air discharge opening disposed over said burner cone and a fuel vaporizer comprising a T pipe-fitting adapted to register with in said oil inlet duct.

5. An oil burner, comprising a burner bowl having a plurality of air inlet openings and a central upstanding burner cone having an oil supply duct extending substantially centrally vertically thereof, an air supply conduit overarching said burner bowl having downturned ends connected to said air inlet openings of the burner bowl and a depending air discharge opening disposed over said burner cone, and a fuel vaporizer comprising a T pipe-fitting the lower portion of the base thereof being of smaller diameter than the upper to register within said oil inlet duct and to form a shoulder to position it therein.

6. An oil burner, comprising a burner bowl having a plurality of air inlet openings and a central upstanding burner cone having an oil inlet duct extending substantially centrally vertically thereof, an air supply conduit overarching said burner bowl having downturned ends connected to said air inlet openings of the burner bowl and a depending air discharge opening disposed over said burner cone and a fuel vaporizer comprising a T pipe-fitting adapted to register within said oil inlet duct, each end of the transverse portion thereof discharging substantially flush with the lower end of the depending air discharge opening of said air supply conduit whereby the upper portion of the transverse portion of said T pipe-fitting may provide deflecting means to more thoroughly vaporize the oil before discharge from said fitting and ignition.

7. An oil burner, comprising a burner

- bowl having a plurality of air inlet openings and a central upstanding burner cone having an oil inlet duct extending substantially centrally vertically thereof, an air supply conduit overarching said burner bowl having downturned ends connected to said air inlet openings of the burner bowl and a depending air discharge opening disposed over said burner cone, said conduit having the portion above the discharge opening downwardly deflected to provide a surface for deflecting the heated air down through said discharge opening, and a fuel vaporizer comprising a T pipe-fitting adapted to register within said oil inlet duct.
8. An oil burner, comprising a burner bowl having a burner cone provided with means to supply oil upwardly therethrough, a fuel vaporizer mounted on said cone and connected with said oil supply means having means to deflect oil downwardly therein above said oil supply means and means to deliver oil vapor in transverse jets above said burner cone and means to discharge air downwardly upon said vaporizer and burner cone.
9. An oil burner, comprising a burner bowl having a burner cone provided with means to supply oil upwardly therethrough, a fuel vaporizer mounted on said cone and connected with said oil supply means having means to deliver oil vapor in transverse jets above said burner cone and means to discharge air downwardly upon said vaporizer and burner cone.
10. An oil burner, comprising a burner bowl provided with means to supply oil upwardly therethrough, a fuel vaporizer mounted on said bowl and connected with said oil supply means having means to deflect oil downwardly therein above said oil supply means and means to deliver oil vapor
- in transverse jets above said burner bowl and means to discharge air downwardly upon said vaporizer and burner bowl.
11. An oil burner, comprising a burner bowl provided with means to supply oil upwardly therethrough, a fuel vaporizer mounted on said bowl and connected with said oil supply means having means to deliver oil vapor in transverse jets above said burner bowl and means to discharge air downwardly upon said vaporizer and burner bowl.
12. An oil burner, comprising a burner bowl having a burner cone provided with means to supply oil upwardly therethrough, a fuel vaporizer comprising a T pipe-fitting having a base mounted on said cone and connected with said oil supply means and lateral ports adapted to deliver oil vapor in transverse jets above said burner cone and means to discharge air downwardly upon said vaporizer and burner cone.
13. An oil burner, comprising a burner bowl provided with means to supply oil upwardly therethrough, a fuel vaporizer comprising a T pipe-fitting having a base mounted on said bowl and connected with said oil supply means and lateral ports adapted to deliver oil vapor in transverse jets above said burner bowl and means to discharge air downwardly upon said vaporizer and burner bowl.
14. An oil burner, comprising a burner bowl provided with means to supply oil upwardly therethrough, a fuel vaporizer mounted on said bowl and connected with said oil supply means to deliver oil vapor in jets outwardly above said burner bowl and means to discharge air downwardly upon said vaporizer and burner bowl.

In testimony whereof I affix my signature.
EUGENE J. JALBERT.
